CLAIM

The ornamental design for a bicycle handlebar grip, as shown and described.

DESCRIPTION

FIG. 1 is a reduced perspective view of a bicycle handlebar grip showing my new design, the portion of a handlebar being shown in broken lines for illustrative purposes only;

FIG. 2 is a reduced perspective view of the side opposite that shown in FIG. 1, the broken lines being for illustrative purposes only;

FIG. 3 is a reduced end perspective view thereof, the broken lines being for illustrative purposes only;

FIG. 4 is a side elevational view thereof;

FIG. 5 is an elevational view of the side opposite that shown in FIG. 1;

FIG. 6 is a top plan view thereof;

FIG. 7 is an end elevational view taken from the right of FIG. 5, the bottom surface being smooth and following the contours shown.
